(57) **CLAIM**

The ornamental design for an underwire bra, as shown and described.

DESCRIPTION

FIG. 1 is an isometric view of an underwire bra showing the new design in position of use, it being understood that the straps broken lines are for illustrative purposes only and form no part of the claimed design;

FIG. 2 is an enlarged front elevation view thereof, it being understood that the straps have been broken away for convenience of illustration;

FIG. 3 is a front elevation view of FIG. 2;

FIG. 4 is a side elevation view of FIG. 2 showing the complete appearance of the straps;

FIG. 5 is a top plan view of FIG. 2; and,

FIG. 6 is a bottom plan view of FIG. 2.
